(57) **CLAIM**

We claim the ornamental design for the precision screw driver, as shown and described.

DESCRIPTION

FIG. 1 is a perspective front top view of a precision screw driver.

FIG. 2 is a perspective rear bottom view of the precision screw driver.

FIG. 3 is a top view of the precision screw driver.

FIG. 4 is a side view of the precision screw driver.

FIG. 5 is a rear view of the precision screw driver; and,

FIG. 6 is a front view of the precision screw driver.

The design is the external appearance of the precision screw driver as shown in the drawings. The broken lines showings of the screw driver blade are for environmental purposes only and form no part of the claimed design.
